United States Patent Office

E. M. KIMBALL, OF TOLEDO, OHIO.

Letters Patent No. 69,103, dated September 24, 1867.

IMPROVEMENT IN WATCH-KEYS.

The Schedule referred to in these Letters Patent and making part of the same.

TO ALL WHOM IT MAY CONCERN:

Be it known that I, E. M. KIMBALL, of Toledo, in the county of Lucas, and State of Ohio, have invented a new and useful Improvement in Watch-Keys; and I do hereby declare that the following is a full, clear, and exact description of the same, reference being had to the accompanying drawing, making a part of this specification, in which—

Figure 1 is a side view, on an enlarged scale, of a watch-key constructed according to my invention.

Figure 2 is an edge view of the same, also on an enlarged scale.

Similar letters of reference indicate corresponding parts in both figures.

It is a frequent occurrence that the cases of a watch open with such difficulty that the thumb-nail is not stiff or strong enough to open them in the usual manner, which necessitates the use of some article or implement for the purpose, such, for instance, as a knife-blade, which not only causes considerable trouble, but also much vexatious delay whenever for any purpose it is desired to open the watch.

This invention is designed to obviate this inconvenience, and it consists in the construction of the winding-key of a watch with a blade or sharp edge, formed thereon in such manner that the said key constitutes a very efficient implement for opening the cases; and one which may be used with great convenience, and without any appreciable loss of time.

To enable others to understand the nature and construction of my invention, I will proceed to describe it with reference to the drawings.

The "socket" of the winding-key is shown at *a*, and *b* represents the head or "thumb-ring" thereof, the socket being made of any usual or suitable form and material, and the thumb-ring being made of metal wire or other proper material, and fitted into or attached to the socket in any appropriate manner. Formed at the innermost portion of the thumb-ring, where it is joined to the socket, is a short neck, *a'*, upon which is placed the swivel *c*, by means of which the key is attached to the guard or chain of the watch. The outermost portion or end of the thumb-ring *b* is made flat upon each side, but with the said sides sloping towards each other in such manner that the outer circumference of the aforesaid end of the thumb-ring is brought to a moderately sharp edge, as shown at *b'*, and more plainly indicated in fig. 2, or, in other words, the said outermost end or portion of the thumb-ring is formed into a kind of blade, the edge of which may be forced under the edges of the watch-case in order to open the said case.

When it is desired to thus open the watch-case, the sharp edge of the blade *b'* is inserted underneath the edge of that lid thereof which it is desired to raise or open, and the said blade is then pushed outward in the same direction with reference to the lid that the thumb-nail is pushed outward in opening the case with the thumb-nail in the usual manner, which causes the lid to be forced outward and opened in the same way.

By this means the watch-case may be very easily and conveniently opened without danger of breaking or injuring the thumb-nail, as in the common manner of opening the case, and without the delay and trouble occasioned by using an implement for the purpose not specially designed therefor.

What I claim as new, and desire to secure by Letters Patent, is—

A watch-key, constructed with a sharp edge or blade, *b'*, substantially as herein set forth, for the purpose specified.

E. M. KIMBALL.
